Eric Schinger.

ATTORNEY

UNITED STATES PATENT OFFICE

WILLIAM C. EMBURY, OF WARSAW, NEW YORK

PORTABLE ELECTRIC LANTERN

Application filed March 17, 1931. Serial No. 523,363.

This invention relates to portable electric battery lamps and has for its object to provide such a lamp with means whereby the light head may be either compactly nested 5 into the casing of the lamp or bodily withdrawn from it and placed into any vertically angular position to the base of the lamp formed by the case thereof.

Another object of this invention is to provide an automatic electric switch with which the electric circuit for operating the incandescent light of the lamp is automatically closed or opened on the movement of the light head out of or into the casing.

Another object of this invention is to so construct the casing of the lamp that the light from the light head can project from the casing while the head remains nested in the casing.

Another object of this invention is to provide a switch for the portable battery lamp with which the electric circuit is automatically opened and closed on the raising and lowering of the light head out of the casing 25 of the lamp and with which the electric circuit may be manually opened and closed while the light head remains nested in the casing of the lamp.

Other objects and attendant advantages 30 will become more readily apparent from the detailed description of the invention reference being had to the accompanying drawings in which.

Figure 1 is a side elevation of the portable battery lamp with the light head in its elevated position.

Figure 2 is a vertical sectional view of the portable lamp, the section being taken on the line 2x-2x of Figure 1.

Figure 3 is a vertical sectional view of the casing of the lamp, the section being taken on the line 3x-3x of Figure 1.

Figure 4 is a top plan view of a slightly modified form of the portable lamp with the light head in its elevated position.

Figure 5 is an end elevation of the modified form of lamp, with the light head nested in the casing.

Figure 6 is a rear elevation of the modified

form of the lamp, with the light head in place in the casing.

Figure 7 is a partial end elevation and vertical sectional view of the modified form of the lamp.

Figure 8 is a horizontal sectional view of the modified form of the lamp, the section being taken on the line 8x-8x of Figure 7.

In the several figures of the drawings like reference numerals indicate like parts.

The portable electric lamp forming the subject matter of my present invention has a rectangular casing 1 which is rounded at both ends. In the middle of one side of the casing is provided a cylindrical pocket or well 2. In this pocket are mounted to swing diametrically opposite each other a pair of arms 3 and 4 which curve toward each other and have the lug 5 swiveled between the outer ends thereof. The pair of arms are thus connected together at their outer ends and swing as one into and out of the pocket 1 as illustrated in Figure 2. The lug 5, which is swiveled between the outer ends of the arms, supports the light head 6 and permits this head to swing in an arc between the arms 3 and 4. The light head carries at the back a cover 7 and on this cover is provided a suitable handle 8 with which the cover and the head is manipulated.

When the lamp is not used, the light head 6 is nested into the cylindrical pocket or well 2 and this is done by turning the light head 6 downwardly between the arms 3 and 4 while simultaneously swinging these arms in the opposite direction down into the pocket until the cover 7 rests on the casing and has closed the top of the pocket 2 as illustrated in dotted lines in Figure 2. A double jointed action

is thus provided for the arms and head and this makes it possible to quickly swing the arms and the head out of or into the pocket as above described. In closing the pocket 2 the edge of the cover 7 engages into the circular sealing channel 9 surrounding the pocket 2.

To use the lamp the cover 7 and head 6 are lifted and gradually swung outwardly while the arms 3 and 4 swing up out of the cylindrical pocket in the casing to a point where the

head is free to be swung individually to assume the angle which will direct the light to the spot which is to be lighted. As illustrated in dotted lines in Figure 1, the head may be placed even into a vertical position.

As illustrated in Figure 1, sufficient room is provided within the casing 1 between the pocket 2 and the rounded ends to accommodate the dry cells 10 and 11 one at each end of the casing. These cells are inserted into the casing by removing the back 12 thereof, suitable locking means being provided to removably hold the back in place on the casing.

The two electric cells are electrically connected in series with each other, a switch and the light 13. This connection is diametrically illustrated in Figure 3. The switch illustrated in this figure is automatically operated when the arms 3 and 4 are raised or lowered. As illustrated in Figure 1 the pivot pin 14 carried keyed to the arm 3 is hollow and thru it passes the wire 15 which connects the switch with the incandescent light 13. The switch comprises a fixed contact member 16 to which the wire 15 is connected and the spring contact member 17 to which the battery is connected. Both of these contact members are insulated from each other and the casing on which they are mounted. The hollow pivot pin 14 carries on the free end thereof a cam 18 made up of suitable insulating material and this cam is so positioned with relation to the arm 15 that when this arm is raised the cam rotates and forces the spring contact member into contact with the fixed contact member 16 so that the electric circuit is closed and the light in the light head lighted as soon as the light is withdrawn from the pocket in the casing and placed in an elevated position.

When the light head is lowered and moved back into the pocket of the casing the reverse takes place because the swinging of the arm 15 downwardly rotates the cam 18 on the pivot pin 14 away from the spring contact 17 so that this contact can move away from the contact 16 and open the circuit. This extinguishes the light automatically when the light head is placed back into the casing.

So far I have described my invention as a portable lamp which can only be used when the light head is withdrawn from the casing so that it can be aimed at the particular spot which is to be illuminated by its light. In Figures 4 to 8 inclusive I have illustrated a slightly modified form of my portable lamp which is designed to make this same type of lamp suitable as a hand lantern.

As illustrated in these figures the construction of the casing, the light head and its mounting remain practically the same as that described in connection with Figures 1 to 3 inclusive. The difference between these two constructions is in the opening which is provided in the bottom 20 of the pocket 2 and

the opening 21 which is provided in the back 12 of the casing. These two openings are in line with each other and the light head 6 when it is located within the casing. Light from the light in the light head is thus projected from the back of the casing 1 when the light in the light head is lighted.

In order to permit the lighting of the light in the light head while the light head is located within the casing, a manually operated switch member 22 is provided. This member comprises a short lever which projects thru an opening in the casing and is suitably pivoted on the inside of the casing. A cam member 23 is formed on the inside of the lever and this cam member is adapted to force the spring contact member 17A in contact with the fixed contact member 16A when moved in one direction and allow the spring contact member 17A to spring away from fixed contact member 16A when moved in the opposite direction. The spring contact member 17A is formed from the same strip of metal as the contact member 17 which is operated by the cam 18 and the fixed contact member 16A is formed from the same strip of metal from which the fixed contact member 16 is formed and their electrical connection with the battery and the incandescent light is the same as that described in connection with Figure 3. In this way cam 18 will automatically operate the light circuit when the light head is raised out of or lowered into the casing while the manually operated switch member with its cam member 23 will operate the light circuit in the same way when it is desired to light the light or turn it off while the light head is located within the casing.

I claim:

1. In a portable battery operated lamp the combination of a casing having a pocket therein, a pair of curved arms pivoted within said pocket to have its outer ends swing in and out of said pocket, a light head swiveled on said arms to swing between and over the arch formed by said pair of arms, said arms being adapted to swing and nest into said pocket and said light head being adapted to swing between said arms and nest into said pocket.

2. In a portable battery operated lamp the combination of a rectangular casing having a pocket formed in the middle thereof, cell containers within said casing one on each side of said pocket, a cover removably fastened to the back of said casing to close said cell containers, a pair of curved arms mounted to swing within said pocket, a light head swiveled between said arms, a cover carried at the back of said light head and overhanging said light head, said cover being adapted to close said pocket with said light head and its arms nested within said pocket.

3. In a portable battery lamp the combi-

nation of a casing having a pocket provided therein, an arm mounted to swing within said pocket, a light head swiveled on said arm, a pivot pin carried by said arm and adapted to turn therewith, a switch, and operating means carried by said pivot pin for operating said switch on the swinging of said arm.

4. In a portable battery operated lamp, a base having a pocket therein, an arm pivoted within said pocket to have its outer end swing in and out thereof, a combined light head and cover swiveled on the outer end of said arm to have the light head and cover swing bodily out of said pocket so as to open said pocket by means of said cover when raising the light head bodily out of said pocket and close said pocket when lowering said light head into said pocket on the swinging of the outer end of said arm out of and into said pocket.

5. In a portable battery operated lamp having an electric circuit, a base having a pocket therein, an arm pivoted within said pocket and adapted to have its outer end swing in and out thereof, a light head swiveled on the outer end of said arm to bodily swing in and out of said pocket on the swinging of said arm and permit an independent swinging of said light head on said arm on the outside of said pocket, a switch for opening and closing the electric circuit for operating the lamp and means operated on the swinging of said arm for opening and closing said circuit.

6. In a portable battery operated lamp, a base having a pocket therein, a battery container provided on each side of said pocket within said base, a pair of arms mounted to swing within said pocket at diametrically opposite points of each other, a light head swiveled between the outer ends of said pair of arms, a switch operated on the movement of said pair of arms, an electric circuit connecting the batteries within said battery containers with each other and said switch and electric connecting means carried by said pair of arms for connecting the light in said light head with the batteries and said switch.

7. In a portable battery operated lamp the combination of a casing having a pocket therein with openings at opposite ends thereof, a light head mounted within said pocket in line with the openings and with its light focused thru one of the openings, and supporting means pivoted on said casing for moving said light head into and out of the other of the openings of said pocket and supporting said light head on the inside and outside of said casing.

8. In a portable battery operated lamp the combination of a casing having a pocket in one side thereof with a hole in the end thereof, a light head mounted within said pocket with its light focused thru the hole in the end of said pocket, an electric circuit for operating the light in said light head, means for moving said light head into and out of the entrance into said pocket, means operated by said first named means to open and close said electric circuit on the movement of said first named means and an electric switch adapted to open and close said electric circuit with the light head held stationary within said pocket.

9. In a portable battery operated lamp the combination of a casing having a pocket extending from one side of the casing to the other and having an opening in both ends in line with each other, a light head, combined supporting and swivel means for supporting said light head in line with one of said openings within said pocket and moving said light head in line with said pocket from the other of said openings and supporting said light head on the outside of said casing angularly to said pocket.

10. In a portable battery operated lamp the combination of a battery casing having a pocket therein, an arm mounted to swing on said casing, a light head swiveled on the end of said arm, said arm being adapted to bodily swing said light head in and out of said casing and a cover carried by said head adapted to close said pocket and locate said head in a predetermined position within said pocket.
